UNITED STATES PATENT OFFICE.

THEODORE J. LOWERY, OF WASHINGTON, DISTRICT OF COLUMBIA.

DESIGN FOR A SPOON.

47,305.

Specification for Design.

Patented May 4, 1915.

Application filed January 4, 1915. Serial No. 522. Term of patent 3½ years.

To all whom it may concern:

Be it known that I, THEODORE J. LOWERY, a citizen of the United States, residing at No. 1421 F street northwest, Washington, District of Columbia, have invented a new, original, and ornamental Design for Spoons, of which the following is a specification, reference being had to the accompanying drawing, forming part thereof.

The figure is a plan view of a spoon showing my new design.

I claim:

The ornamental design for spoons, as shown.

THEODORE J. LOWERY.

Witnesses:

CARL SCHIMMEL,
BONFORD BONIFACE.
